CLAIM

The ornamental design for a misting fan, as shown and described.

DESCRIPTION

FIG. 1 is a perspective view of a misting fan showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof;

FIG. 8 is another perspective view thereof; and,

FIG. 9 is an assembled view for showing the misting fan is assembled to a base, wherein the broken line portion is for illustrative purpose only and forms no part of the claimed design.
